UNITED STATES PATENT OFFICE.

JAMES E. CLENNY, OF CHICAGO, ILLINOIS, ASSIGNOR TO THE SEFTON MANUFACTURING COMPANY, OF CHICAGO, ILLINOIS, A CORPORATION OF INDIANA.

PACKING AND SHIPPING BOX.

1,169,238.

Specification of Letters Patent. Patented Jan. 25, 1916.

Application filed September 28, 1912. Serial No. 722,836.

To all whom it may concern:

Be it known that I, JAMES E. CLENNY, a citizen of the United States, residing at Chicago, in the county of Cook and State 5 of Illinois, have invented certain new and useful Improvements in Packing and Shipping Boxes, of which the following is a specification.

My invention relates to boxes made of 10 paper board, preferably double-faced corrugated paper board, and intended for the packaging and shipping of different articles.

The object of my invention is to produce a 15 novel and simple construction of box particularly adapted for the shipment of liquid articles contained in bottles and the like and designed to comply with the rigid requirements of railroads and other transportation companies.

20 My shipping box is characterized by the provision of fillers and a waterproofed inner shell, the filler being made of wood or like material which is incapable of being destroyed or weakened by liquid in case any 25 one of the bottles should become broken or in case of leakage. The inner shell or box being waterproofed prevents the escape of the liquid and moreover the corrugated paper board, of which I prefer to make such 30 shell, is adapted to absorb on its inner side any liquid which may thus be within the inner shell. I also contemplate employing a pad on the bottom of the box for absorbing such liquid and also a top closure which 35 is waterproofed only as to its outer side and which when in position is adapted to complete the sealing of such shell which is otherwise made of a single piece.

In the use of paper board for packing 40 and shipping boxes, particularly as a substitute for wooden boxes, objection has been made by railroads and other transportation companies especially as regards the shipping of liquids in bottles, the bottles being liable 45 to become broken and the contents being liable to leak from the box to the damage of other goods and to also destroy or weaken the box itself. Moreover, when fillers of paper board are used the liquid absorbed by such 50 filler is liable to destroy its strength or so weaken it that the other bottles contained in the box will strike each other and cause further breakage. The object of my present invention is to overcome these difficulties and 55 objections by providing a packing or ship-

ping box in which any liquid from broken bottles is retained in the box and this without destroying or weakening it or any of its parts, including the filler, which is made of material other than the usual paper 60 board, such as wood.

In the drawing Figure 1 is a perspective of my box with the outer shell opened out and with the closure of the inner shell removed; Fig. 2 a cross section of the box in 65 closed condition but on a larger scale than in Fig. 1; Fig. 3 a detail perspective view of one of the corners of the inner shell; Fig. 4 a sectional plan of one of the corners of the inner shell; Fig. 5 a sectional detail on 70 the line 5—5 of Fig. 4 and Fig. 6 a detail view of a modified form of construction.

I prefer to make the entire box with the exception of the filler of double face corrugated paper board, but in the broader aspect of my invention this is not essential particularly as to the inner shell, which, as shown in Fig. 6 might be made of single face corrugated paper board as hereinafter explained.

80 Referring to Figs. 1 to 5 the box proper comprises two main parts, to wit an outer box or shell and an inner box or shell. The outer shell which may be of any suitable proportions and dimensions is provided 85 with four side walls 1, whose upper and lower edges are provided with the extensions 2, which latter when folded inwardly and downwardly constitute the top and bottom closures of the entire box. After these 90 closures have been thus folded the box may be sealed over the joint in suitable manner as by means of the sealing tape 3, Fig. 2.

95 The inner shell is made from a single piece of paper board which in the present instance is double faced corrugated paper board. As shown this inner shell comprises a bottom 4, and four side walls 5 hinged thereto and corresponding substantially in size with the side walls 1 of the outer shell 100 and in addition such inner shell comprises the triangular corner folds 6 which are folded upon each other and against the outer faces of two of the opposite side walls of the inner shell. By preference the corrugated character of these corner folds is destroyed by crushing down the corrugations thereof thereby permitting easier folding of these corner folds and narrowing the space 105 between the inner and outer shells. In order 110

to hold these corner folds in place and secure them to their side walls suitable means may be employed, as for instance the hook 7, one arm of which is passed downwardly in the 5 corrugations of the side wall and the other arm of which is passed downwardly through the corrugations of the outermost corner fold, Figs. 4 and 5.

The outer faces of the inner shell, that is 10 the outer facing strip thereof, is waterproofed in any suitable manner but by preference the remainder of the paper board material, that is the inner facing strip and the corrugated strip, are left in their usual 15 condition, with the result that they are capable of absorbing any liquid within the shell and of thereby acting as a sponge. If desired the pad which may also be made of double faced corrugated paper board or 20 of the single faced variety but not waterproofed, may be used in the bottom of the inner shell for the special purpose of absorbing any liquid from the bottles, such a pad being indicated in the drawing at 8, 25 Fig. 2.

Within the inner shell is arranged the 30 filler 9 having any suitable number of compartments or pockets and made of wood or any other rigid material incapable of being destroyed or weakened by liquid, so that in case of the breakage of one bottle the other 35 bottles would not be liable to come in contact with each other, the wood maintaining under all conditions the proper relative position and spacing of the bottles.

Boxes containing liquids in glass are 40 generally marked to indicate which side should be kept up so that theoretically it would be unnecessary to provide any closure for the top of the inner shell, but as in practice the directions on the box are not always observed by the persons handling the boxes in transit, I prefer to provide a closure which not only closes but seals the top 45 of the inner shell. For this purpose I employ a sheet 10 of double faced corrugated paper board which is water proofed on that side exposed to the interior of the inner shell. This closure is provided with marginal extensions 11 which are tucked downwardly between the side walls of the inner 50 and outer shells, Fig. 2.

In Fig. 6 I have shown a modified form 55 of construction according to which the inner shell instead of being made of double faced

corrugated paper board is made of the single faced variety, such single faced paper being indicated at 12.

I claim:

1. A shipping box made of corrugated 60 paper board waterproofed as to its outer face and comprising a bottom and side walls hinged thereto, and rigid fillers within such box.

2. A shipping box made of corrugated 65 paper board waterproofed as to its outer face and comprising a bottom and side walls hinged thereto, a top closure waterproofed as to its inner face which is exposed to the interior of the box and having marginal extensions enveloping the top portions of the side walls, and rigid fillers within such box.

3. A shipping box made of double faced 70 corrugated paper board water-proofed as to its outer facing strip only and comprising a bottom, and side walls hinged thereto, and rigid fillers within such box.

4. A shipping box made of double faced 75 corrugated paper board water-proofed as to its outer facing strip only and comprising a bottom, side walls hinged thereto and corner folds hinged to the side walls and faces of the side walls, the corrugations of such corner folds being crushed down, and rigid 80 fillers within such box.

5. A shipping box made of double faced 85 corrugated paper board waterproofed as to its outer facing strip only and comprising a bottom, and side walls hinged thereto, a 90 closure made of the same character of double faced corrugated paper board and fitting upon the top of such box to seal it against the escape or leaking of liquid from within the box.

6. A shipping box comprising an outer 95 shell of corrugated paper, and an inner shell therein made of corrugated paper board waterproofed as to its outer facing strip only.

7. A shipping box comprising an outer 100 shell of corrugated paper, an inner shell therein made of corrugated paper board waterproofed as to its outer facing strip only, and rigid fillers within such box.

JAMES E. CLENNY.
